(57) **CLAIM**

The ornamental design for a screwdriver for rectopexy, as shown and described.

DESCRIPTION

FIG. 1 is a bottom left perspective view of a screwdriver for rectopexy in accordance with the new design;

FIG. 2 is a left side isometric view thereof;

FIG. 3 is a right side isometric view thereof;

FIG. 4 is a bottom isometric view thereof;

FIG. 5 is a top isometric view thereof;

FIG. 6 is a rear right side isometric view thereof;

FIG. 7 is a front right side isometric view thereof;

FIG. 8 is a top perspective view of the screwdriver for rectopexy of FIG. 1, with an outer sleeve omitted to show aspects of the design that are not apparent in the other views;

FIG. 9 is a top isometric view thereof;

FIG. 10 is a bottom isometric view thereof;

FIG. 11 is a right side isometric view thereof;

FIG. 12 is a left side isometric view thereof;

FIG. 13 is a front right side isometric view thereof;

FIG. 14 is a rear right side isometric view thereof;

FIG. 15 is a bottom left perspective view of the outer sleeve of the screwdriver for rectopexy of FIG. 1, with the other parts omitted for ease of illustration;

FIG. 16 is a left side isometric view thereof;

FIG. 17 is a right side isometric view thereof;

FIG. 18 is a top isometric view thereof;

FIG. 19 is a bottom isometric view thereof; and,

FIG. 20 is a rear right side isometric view thereof.

The broken lines shown in FIGS. 1-14 and 20 represent the boundaries of the claimed design, with the lines themselves and the areas within them forming no part of the claimed design.
